UNITED STATES PATENT OFFICE.

ARTHUR E. CLEMENTS, OF SOUTH JACKSONVILLE, FLORIDA.

COMBINED JACK AND PULLER.

1,395,945.

Specification of Letters Patent.

Patented Nov. 1, 1921.

Application filed December 4, 1920. Serial No. 428,320.

To all whom it may concern:

Be it known that I, ARTHUR E. CLEMENTS, a citizen of the United States, residing at South Jacksonville, in the county of Duval and State of Florida, have invented new and useful Improvements in Combined Jacks and Pullers, of which the following is a specification.

While my present invention is primarily adapted for use as a stump puller, the same may be used with equal efficiency in other connections, as for instance, as a jack or similar lifting device.

My object is the production of a device of this character which shall be of a simple nature, cheaply constructed, easily operated, and thoroughly efficient in operation.

A further object is the production of a device of this character in which a body member having angularly disposed foot portions or legs is provided, said body having its upper portion formed with barrels whose bores are threaded and whose confronting surfaces are grooved longitudinally to provide guides for a stem or shank that has an outstanding lug passing between the guides, said lugs serving as a rest for an element to be elevated or having attached thereto a chain provided with grapple hooks to engage with the stump of a tree to be raised, the shank having its upper portion provided with a lateral portion provided with spaced openings through which pass the non-threaded ends of screws that enter the referred to threaded openings in the barrels. On the non-threaded ends of the screws are worm wheels which rest on the top surface of the head, the said worm wheels being engaged by a worm on a shaft that is provided with an operating handle, and the turning of this shaft will cause the turning of the screws and the longitudinal movement of the head and shank and the engaging element or elements carried thereby.

The foregoing, and other objects which will appear as the nature of the invention is better understood, may be accomplished by a construction, combination and operative arrangement of parts, such as is illustrated by the drawings which accompany and which form part of this application.

In the drawings:-

Figure 1 is a view showing the device employed for pulling the stump of a tree.

Fig. 2 is a view of the device employed as an ordinary vehicle jack.

Fig. 3 is a front elevation of the improvement.

Fig. 4 is a top plan view thereof.

Fig. 5 is a sectional view on the line 5—5 of Fig. 4.

Fig. 6 is a sectional view on the line 6—6 of Fig. 3.

As disclosed by the drawings, the body portion 1 of the improvement has depending from its lower corners outwardly directed downwardly rounded legs 2. The outer end of each of the legs has a flat substantially square or rectangular enlargement providing the same with what I will refer to as foot portions 3. The foot portions 3 prevent the legs from sinking into the ground, when the device is employed as a stump puller, as illustrated in Fig. 1 of the drawings. Also the foot portions provide a firm support for the device when employed as a jack, as illustrated in Fig. 2 of the drawings. The body 1 is of a substantially rectangular formation, having its outer face flat, but its inner face, from its corners rounded, providing what I will term barrels 4. By reference to the drawings, it will be seen that the barrels, on the inner face of the body are spaced a suitable distance away from each other, and also that each of the barrels has a vertically disposed slot 5 that terminates with the inner straight wall 6 of the body 1. These alining slots provide guideways for a cross sectionally rectangular shank 7. The shank may be of any determined length, and has at its outer end a widened and laterally extending portion which I shall term a head 8. The head has adjacent its ends, round openings therethrough, and through these openings pass the non-threaded portions 9 of screws 10. The portion 10 of each of the screws, which projects beyond the head has keyed or otherwise secured thereto a worm wheel 11. Between the worm wheels, the head is formed with spaced outstanding lugs 12—12 respectively which have openings that provide bearings

95
100

- for a shaft 13. The shaft, between its bearings, has secured thereon a worm 14, and the worm is in mesh with the respective worm wheels. The outer end of the shaft has a 5 preferably removable operating handle 15. The shaft is held against longitudinal movement in its bearings by the contacting engagement of the ends of the worm with the bearings 12.
- 10 Each of the barrels has a vertical opening therethrough, the said openings being disposed inward of the legs 2, and the openings are threaded to receive the screws 10 therein. These openings are indicated by the numeral 15 16 and the threads therein are pitched at opposite angles which is also true with respect to the pitch of the threads on the screws 10. Thus by turning the handle to revolve the shaft the head 8 may be raised 20 or lowered with respect to the body, and effectively held at such adjustment by the coengagement of the screws with the threads in the bores of the barrels.

On the inner face of the shank 7 there is 25 integrally formed an outstanding lug 17 which is guided between the straight confronting walls of the barrels between the guide slots or grooves therein. This lug, when the device is employed as a jack, as 30 illustrated in Fig. 2 of the drawings, engages the portion of a vehicle to be elevated. The lug is formed with a transverse notch 18 from the upper edge thereof, the said notch being preferably widened and rounded 35 at the lower portion thereof. This slot provides the lug with two engaging surfaces, when the device is employed as a jack and also serves as a means whereby an enlarged link 19 at one end of a chain 20 may be received therein. The outer link of the 40 chain has connected therewith grapple hooks 21 and these hooks are designed to engage with the trunk of the tree, when the device is employed as a stump puller.

45 It is believed that the construction and operation of the improvement will be perfectly apparent to those skilled in the art to

which such inventions relate, by reference to the drawings, when taken in connection with this description, and that a further detailed 50 description will not be considered necessary.

Having described the invention, I claim:

1. In a device for the purpose set forth, a body having depending legs at the outer corners thereof, screw members having oppositely pitched threads vertically movable through threaded openings in the body, a shank having an outstanding lug thereon guided through the body, a head on the shank having openings receiving the non-threaded upper ends of the screws, worm wheels secured to said ends and resting on said head, a shaft journaled in the head and having a worm engaging the worm wheels, and an operating handle for the shaft. 65

2. In a device for the purpose set forth, a body having outwardly rounded depending legs at the outer corners thereof terminating in flat feet, said body having spaced barrels formed with threaded bores, on the inner 70 face thereof, which are spaced away from each other and which have the threads in their bores arranged at right and left hand pitches respectively, said barrels having their confronting faces grooved, a cross sectionally 75 rectangular shank guided through the grooves, having a notched outstanding lug guided between the barrels, grapples removably secured to the lug, a lateral head on the outer end of the shank, screws having right and left hand pitched threads respectively engaging in the bores of the respective barrels, said screws having non-threaded portions which pass through portions of the head, worm wheels secured to the 80 last mentioned portions of the screws and resting on the head, spaced outstanding lugs on the head between the worm wheels and a shaft journaled therein, a worm on the shaft 85 between the lugs engaging with the worm wheels, and a removable operating handle for the shaft. 90

In testimony whereof I affix my signature.

ARTHUR E. CLEMENTS.
